DRAFT GEARS

Emil H. Blattner, Williamsville, N.Y., assignor to Symington Wayne Corporation, a corporation of Maryland

Filed Aug. 16, 1956, Ser. No. 604,553

7 Claims. (Cl. 213—46)

This invention relates to draft rigging.

The A.A.R. committee on couplers and draft gears is now contemplating increasing the length of the present standard 24½" draft gear pocket to as much as 36" in order to accommodate long travel draft gears of high capacity sufficient to absorb the greater shocks, mainly under buffing forces, to which freight cars are being subjected in humping and other service.

The primary object of this invention is to provide a draft rigging which not only is capable of affording a draft gear pocket of the extra length contemplated, but incorporates, in the form of a reversible rear follower member of particular construction, means for reducing the pocket to one of present standard length when, because of a breakdown or otherwise, it is desired or necessary to apply a draft gear of the present standard length.

Another object of the invention is to provide an improved draft rigging wherein a draft gear pocket of the maximum length contemplated may be converted selectively to accommodate draft gears of both the present standard and intermediate lengths.

An additional object of the invention is to provide for a draft gear pocket of the maximum length contemplated, an improved long travel draft gear of selective travel wherein a plurality of cushioning mechanisms are arranged in tandem, one within and the other rearwardly of a yoke, at least the rear mechanism being a rubber cushion interposed between confronting flat walls of the yoke and a rear follower and the yoke being so connected to an associated coupler as to permit rearward relative movement of the latter coextensive with the travel of the mechanism within the yoke, whereby under buffing forces the straps of the yoke are relieved of stress and metal-to-metal contact is avoided.

A further object of the invention is to provide in a draft rigging an improved reversible rear follower member which in one position serves as a conventional rear follower block and, on reversal, acts as a forward extension of the back stop to decrease the length of the draft gear pocket.

Other objects and advantages of the invention will appear hereinafter in the detailed description, be particularly pointed out in the appended claims and be illustrated in the accompanying drawings, in which:

Figure 1 is a side elevational view of the improved draft rigging of the present invention with portions broken away and shown in section to more clearly illustrate certain of the details of construction;

Figure 2 is a plan view of the draft rigging of Figure 1 with certain portions shown in section;

Figure 3 is a fragmentary vertical sectional view taken along the lines 3—3 of Figure 4 showing the relation between the combined back stop and center filler and reversible rear follower member of the preceding figures and an associated draft gear and yoke when the follower member is reversed to decrease the length of the draft gear pocket.

2

Figure 4 is a plan view partly in section of the structure shown in Figure 3;

Figure 5 is a vertical sectional view taken along the lines 5—5 of Figure 3;

5 Figure 6 is a fragmentary vertical sectional view taken along the lines 6—6 of Figure 7 showing the draft gear pocket adapted to accommodate a draft gear of intermediate length; and

10 Figure 7 is a plan view partly in section of the structure of Figure 6.

Referring now in detail to the drawings, in which like reference characters designate like parts, the improved draft rigging of the present invention is designed to fit

15 between the center sills 1 of a railway car (not shown) and comprises a pair of rear stop lugs 2, one at either side

of the center sills 1, the stop lugs preferably being integral with and forming the front ends of the side walls 3 of a combined back stop and center filler unit 4. The longitudinal spacing between the stop lugs 2 and king post

20 5 of the combined unit 4 is made considerably less than normal by compacting or shortening the unit in that dimension so as to provide between the rear stop lugs 2 and front stop lugs 6 longitudinally spaced therefrom and

also fixed to the center sills, a draft gear pocket 7 of increased length, 36" in the disclosed embodiment. In the combined unit 4 between the rear stop lugs 2 and the king post 5 is a forwardly opening pocket 8 which, for increased strength of the unit, may be interrupted intermediate its height by a horizontally disposed reinforcing

30 web 9 joining the rear stop lugs 2, side walls 3, and king post 5 of the unit, the web being lightened without decreasing its strength by a concave indent 10 in its front edge 11.

Within the center sills 1 forwardly of the combined

35 back stop and center filler unit 4 is a reversible rear follower or stop member 12 having a bifurcated portion forming a pair of longitudinally extending substantially

parallel legs 13 joined at their inner ends by an integral, vertically disposed flat or planar block, block portion or

40 wall 14 adapted in any position to bear against or engage the rear stop lugs 2. Reinforced by horizontally disposed ribs 15 connecting its legs 13 and wall 14, the reversible follower member 12 between its legs has a longitudinally opening recess or cavity 16 which, in the

45 position of the follower member shown in Figures 1 and 2, in which its legs fit between the rear stop lugs 2 and project or extend rearwardly thereof toward the king post 5, enables the legs to straddle the horizontal reinforcing

50 web 9 of the combined unit. While its legs 13 are vertically spaced in that position, when the follower member is reversed in the manner herein contemplated by turning it end for end as well as rotating it through 90° about a horizontal axis, the legs will be horizontally spaced and

55 project or extend into and be disposed at either side of the draft gear pocket 7. Thus, in the latter position, the legs 13 serve as forward extensions of the rear stop lugs 2 and are adapted to straddle or bridge a rear wall 17 of an associated yoke 18 and engage at either side of that wall

60 the rearwardly directed face 19 of a rear follower block 20 or other rear part of a draft gear 21 contained within the yoke, this arrangement being shown in Figures 3—5.

With the rear wall 17 of the associated yoke 18 accommodatable in the recess 16 in the reversible follower mem-

65 ber 12 and able to move rearwardly therein, and the vertically disposed faces 22 at the free ends of the legs

13 then functioning as rear stop lugs in place of the fixed lugs 2, the reduction in the length of the draft gear

70 pocket obtainable by reversal of the reversible follower member will depend entirely on the length of the legs 13, that here intended being down to the 24½" length of

the present standard draft gear pocket.

In the normal position of reversible follower member 12, shown in Figures 1 and 2, in which its legs 13 project rearwardly of the rear stop lugs 2 into the combined unit 4, the flat or planar surface or face 23 of the leg-connecting wall 14 at the opposite end of the unit is especially suited to bear against and serve as the reactance for a rubber rear cushioning unit or mechanism 24 of a selective travel draft gear, the rubber unit preferably being formed in the usual manner of alternating flat metal plates 25 and rubber pads 26. Bearing against the opposite or outer end of the rubber cushioning mechanism is a flat rear wall 27 of a yoke 28 within which is contained a second cushioning mechanism 29 which may be in the form of a rubber, friction or combined rubber and friction draft gear, one of the third type particularly suited for such application being the draft gear of my copending application Serial No. 475,350, filed December 15, 1954.

Since with the rubber cushioning unit 24 interposed between it and the rear stop lugs 2, the cushioning mechanism 29 must be compressible within the yoke 28 for the tandem-arranged mechanisms to cooperate in buff, it is necessary to provide between the yoke and an associated coupler 30 for relative rearward movement of the coupler substantially coextensive with the travel of the cushioning mechanism 29 in order to render the contained cushioning mechanism effective or operative under buffing forces. While the particular structure will depend upon the type of the associated coupler, this in general requires a pin and slot connection with the slots in the yoke straps rearwardly elongated to accommodate the travel of the contained or front mechanism. Thus, for the alternate standard Type "F" coupler of the illustrated embodiment, which, while universally movable relative to a yoke, conventionally is connected to move longitudinally in unison with the yoke by a connecting pin 31, the pin-receiving openings in the yoke straps 32 are rearwardly elongated to provide pin slots 33 of the required length.

The balance of the structure illustrated in Figures 1 and 2 in the main is conventional, the front stop or draft lugs 6 being integral with a combined striking casting and a coupler carrier 34 pocketing a resiliently supported carrier iron 35. However, there are two exceptions. The first is the provision on the front follower block 36 of forwardly extending ears 37 having sockets 38 at their forward ends for engaging the connecting pin 31 above and below the butt 39 of the coupler so as to minimize canting of the front follower block under buffing forces. The second exception is an increase in the length of the shank 40 of the coupler so that the distance between its horn 41 and the striker 34 of the combined striking casting and coupler carrier 34 is sufficient to accommodate the total travel in buff of the draft gear, some 4½" in the illustrated embodiment.

In the disclosures of Figures 1-5, the same construction serves for the application of both a long (4½") travel and a present standard 2½" travel draft gear to the draft gear pocket 7. Thus, the same intermediate cross tie or tie plate 42 underlying the pocket and fixed as by riveting to the bottom flanges 43 on either side of the center sills 1, supports a yoke and included draft mechanism and a rear cross tie or tie plate 44 is adapted to underlie and support either the rear cushioning unit 24 or the reversible rear follower 12, depending on the arrangement used. In the case of the reversible rear follower 12, the rear cross tie 44 supports not only the follower block 14 but also the legs 13 when the latter are directed forwardly, the rear cross tie for this purpose preferably being provided with a pair of transversely spaced longitudinally extending support plates or flanges 45, fixed, as by welding, to one face of the cross tie and adapted, when that face is uppermost, to underlie and engage the legs. The rear cross tie 44, when supporting the rear cushioning unit, is turned upside-down or

reversed so that the support plates 45 hang down out of the way.

As will be noted, the legs 13 of the reversible rear follower member 12 are inset inwardly from the marginal edges of the integral follower block 14 so that when the follower member is in its normal position, adapting the pocket 7 to receive a selective travel draft gear, the lower of the legs 13 has no difficulty in clearing the bottom web 46 of the combined back stop and center filler unit 4. However, if, in addition to the two alternatives thus far described, it is desired to adapt the pocket 7 to take a draft gear of a travel in between the two extremes, some revision in structure is necessary. The main one is the replacement of the reversible rear follower by a rear follower block 47 positioned within and bearing against the rear wall 48 of an associated yoke 49 and having at its ends a pair of rearwardly directed arms 50 straddling the rear wall of the yoke and adapted to bear against the fixed rear stop lugs 2. The use of such a U-shaped rear follower block permits the same fixed rear stop lugs to be employed with all three forms of draft gear, but the bottom web of the preferred combined unit previously described, while having its leading edge set back somewhat from the stop lugs 2, would interfere with the rear wall 48 of the yoke 49 of this third form of draft gear on maximum rearward movement. Consequently, when provision is to be made for this third alternative, the bottom web 46 of the combined unit 4 intermediate its sides, is cut back, as at 51 to clear the rear wall of the yoke.

From the above detailed description, it will be apparent that there has been provided an improved draft rigging affording a draft gear pocket of sufficient longitudinal dimension to accommodate a long travel draft gear, modifiable by means incorporated in the draft rigging to shorten the pocket to accommodate a draft gear of present standard travel and further modifiable by substitution of a different rear follower, to accommodate a draft gear of medium travel. It should be understood that the described and disclosed embodiments are merely exemplary of the invention and that all modifications are intended to be included which do not depart from either the spirit of the invention or the scope of the appended claims.

Having thus described my invention, I claim:

1. In a draft rigging, the combination with center sills and front stop lugs fixed thereto, of rear stop lugs fixed to said sills and defining therewith and with said front stop lugs a draft gear pocket and a member insertible between said stop lugs and selectively positionable to vary the length of said pocket for accommodating draft gears of different length, said member comprising a block portion engageable with said rear stop lugs and a bifurcated portion integral with and projecting longitudinally of said pocket from said block portion, said bifurcated portion in one position of said member being insertible between and extending rearwardly of said rear stop lugs and in another position extending forwardly thereof and being adapted to straddle a yoke of an associated draft gear.
2. In a draft rigging, the combination with spaced front and rear stop lugs longitudinally defining a draft gear pocket, of a rear follower member interposed between said front and rear stop lugs and engaging said rear stop lugs and having a substantially flat front wall, a yoke in said pocket and having a substantially flat rear wall, a plurality of cushioning mechanisms arranged in tandem, one within said yoke and another rearwardly thereof between said flat walls of said follower member and yoke, at least said rearward mechanism being a rubber cushioning unit, and said yoke having a pin and slot connection with an associated coupler for rearward movement of said coupler relative thereto coextensive with travel of said mechanism within said yoke.
3. In a draft rigging, the combination with center sills

and front stop lugs connected thereto, of a combined back stop and center filler unit including rear stop lugs spaced forwardly of a king post of said unit and defining with said front stop lugs a draft gear pocket, a forwardly facing opening in said unit between said rear stop lugs, and a member interposed between said front and rear stop lugs and selectively positionable relative to said unit for varying the length of said pocket to accommodate draft gears of different length, said member including a block portion engageable with said stop lugs and presenting at one end of said member a substantially flat face and a pair of transversely spaced legs integral with and projecting longitudinally from an opposite face of said block portion, said legs in one position of said member projecting into said unit between said rear stop lugs and in another position extending forwardly thereof and being adapted to straddle a rear wall of a yoke and at opposite sides thereof react against a draft gear contained in said yoke.

4. In a draft rigging, the combination with spaced front and rear stop lugs longitudinally defining a draft gear pocket, of a rear follower member interposed between said front and rear stop lugs and engaging said rear stop lugs and having a substantially flat front wall, a yoke in said pocket and having a substantially flat rear wall, a plurality of cushioning mechanisms arranged in tandem, one within said yoke and another rearwardly thereof between said flat walls of said follower member and yoke, at least said rearward mechanism being a rubber cushioning unit, said yoke being universally connected to an associated coupler by a pin riding in slots in said yoke, and said slots being longitudinally elongated sufficiently to permit rearward movement of said coupler relative to said yoke coextensive with travel of said one cushioning mechanism.

5. In a draft rigging, the combination with spaced front and rear stop lugs longitudinally defining a draft gear pocket, of a rear follower member interposed between said stop lugs and engaging the rear thereof and having a substantially flat front wall, a yoke in said pocket and having a substantially flat rear wall, a plurality of cushioning mechanisms arranged in tandem, one within said yoke and another rearwardly thereof between said flat walls of said follower member and yoke, at least said rearward mechanism being a rubber cushioning unit, said yoke being pin and slot connected to an associated coupler for relative universal movement therebetween and relative rearward movement of said coupler coextensive with travel of said one cushioning mechanism, and a front follower interposed between said one mechanism and a butt of said yoke and having arms straddling said butt and engaging on opposite sides thereof a pin connecting said

yoke and coupler for guiding said front follower on rearward movement of said coupler under buffing forces.

6. In a draft rigging, the combination with center sills and front stop lugs fixed thereto, of a combined backstop and center filler unit, said unit including rear stop lugs spaced forwardly of a king post thereof and a substantially horizontally disposed reinforcing web connecting said rear stop lugs and king post intermediate the height of said unit, and a member interposed between said front and rear stop lugs and selectively positionable relative to said unit for varying the length of said pocket to accommodate draft gears of different length, said member comprising a block portion engageable with said rear stop lugs and presenting at one end of said member a substantially flat face, and a pair of transversely spaced, substantially parallel legs projecting from said block portion to an opposite end of said member, said legs in one position of said member extending rearwardly between said rear stop lugs and straddling said web and in another position projecting forwardly of said rear stop lugs and being adapted to straddle a yoke of an associated draft gear for transmitting buffing forces from a draft mechanism contained in said yoke rearwardly through said block portion to said rear stop lugs.

7. In a draft rigging, the combination with center sills and front stop lugs connected thereto, of a combined backstop and center filler unit, said unit including rear stop lugs spaced forwardly of a king post of said unit and defining with said front stop lugs and center sills a draft gear pocket, and a member for adapting said pocket to accommodate a draft gear of shorter length than said pocket, said member comprising a block portion disposed transversely of said pocket and fittable within and engageable with a rear wall of a yoke and a pair of transversely spaced legs extending rearwardly therefrom, said legs being adapted to straddle a rear wall of an associated yoke and each engage one of said rear stop lugs for transmitting buffing forces from a draft mechanism within said yoke to said rear stop lugs.
